ELECTRIC SWITCH

John R. Caldwell and Thomas E. Curtis, Hampton,
Ga., assignors to Southern States Equipment
Corporation, a corporation of Georgia

Application December 14, 1946, Serial No. 716,334

7 Claims. (Cl. 200—48)

1

This invention relates to high voltage electric switches of the type in which the switch-arm is first moved into its closed-circuit location and then heavy pressure is developed between the switch-arm and the stationary contacts; and it refers particularly to rotating the switch-arm and thereby producing the heavy contact pressure. One purpose is to provide a direct and positive means to rotate the arm but only when the arm is in closed circuit location; another purpose is to avoid latches, springs, hooks, or other limiting devices to accomplish this purpose; a third object is to provide a mechanism that transmits and applies the operating power directly and with a minimum of heavy stresses due to unfavorable leverages. Other objects will be evident from the specification and claims.

In the drawings, Fig. 1 shows a small scale view of one pole of one type of switch embodying this invention; Fig. 2 shows in larger scale a side view of the hinge end of the switch; Fig. 3 shows a view of the rocker from the direction 3—3; Fig. 4 is a top view of the hinge members; Fig. 5 is an end view of the jaw contact end of the switch; and Fig. 6 is an expanded diagram explaining one of the operating principles involved.

The base 1 carries two stationary insulators 2, 3 and the rotating insulator 4, which is operable by the crank 5. Integral with the insulator unit 4 is the crank 6. The insulator 3 carries the hinge base 7 which provides a steady bearing for the top of insulator unit 4. The switch-arm structure 8 includes the switch-arm hinge 21, and the rotative switch-arm. The rotative switch-arm includes the terminal 17 with its extension 18 and its bearing shaft 19 and the collar 20, also the tubular arm 22 with its flattened end contact 23. The entire switch-arm structure is pivotally hinged to the hinge base 7 by the hinge pivots 9—9; and the rocker 10 is also hinged to base 7 by the long stationary rocker hinge pivot 11. The link 12 in the form of a bellcrank is mounted on the fourth pivot 13 which is secured to the switch-arm hinge 21; and the upper arm of link 12 receives the rocker swing pin 14 which is supported by rocker 10 and which serves also as the pivot for the universal joint member 15 which in turn is connected by the operating rod 16 to the crank 6.

The bearing shaft 19 is supported by its bearing in switch-arm hinge 21, and the extension 18 on terminal 17 fits loosely through a hole in the lower arm of link 12. The tubular extension 22 is integral with terminal 17, and the flattened end contact 23 is engageable by the jaw con-

2

tacts 24—24. Bolt 25 serves as a stop to prevent over-travel of end 23, and also it provides a means to adjust the spacing of jaw contacts 24—24.

Terminal 17 carries two longitudinal ridges 26—26 which engage with hinge contact members 27—27 when the switch is fully closed. Line terminal 28 is bolted to hinge-base 1; and line terminal 29 is electrically connected with jaw contact 24—24.

Operation is as follows. With the switch fully closed as shown, there is heavy pressure between end contact 23 and jaw contacts 24—24. Also ridges 26—26 are in heavy pressure contact with hinge contacts 27—27. When the crank 5 is turned, crank 6 and rod 16 and member 15 act to move rocker 10 counterclockwise. This moves rocker swing pivot 14 from its position on line C towards a position on line D. Arc AAA is drawn about the center 11 and arc BBB is drawn about the center 13. These arcs closely coincide for a considerable distance and there is enough play in various joints to allow motion of pin 14 from line C to line D without substantially changing the location of pin 13. But link 12 has thereby been definitely rotated counter-clockwise, thereby lifting extension 18, and so terminal 17 and tube 22 are rotated sufficiently to relieve the pressures between these members and contacts 27—27 and 24—24, respectively. Thereupon the switch-arm structure is free to move upwardly.

Further motion of crank 5 continues the counter-clockwise motion of rocker 10. But link 12 keeps pin 13 at a fixed distance from pin 14, and therefore as arc AAA becomes separated from arc BBB pin 13 is lifted from its former position and so switch-arm structure 8 is lifted. Ultimately these members reach the position shown by dotted lines in Fig. 2 and the switch is fully open.

In closing the switch, the reverse motions occur. When the rocker swing pivot 14 reaches its position at line D the end 23 is well between the jaw contacts 24—24, and the ridges 26—26 are between hinge contacts 27—27, motion of rocker swing pivot 14 from line D to line C turns bellcrank 12 clockwise and so extension 18 is forced downward. This gives ample leverage to turn terminal 17 and end 23 so that heavy pressure contact is again established with jaws 27—27 and 24—24, and the switch is again fully closed.

The joints at 9 and at 19 may be bridged if desired by a suitable flexible conductor electrically connected from base 7 to socket 17, thereby replacing the function of projections 26—26 and

jaws 21-27. Various other changes also can be made by one familiar with the art without departing from the purpose and spirit of this invention.

We claim:

1. In an electric switch, a first insulated support and a contact mounted thereon, a second insulated support and a hinge pivot mounted thereon, a switch-arm structure that comprises a switch-arm hinge movable about the hinge pivot and a switch-arm that is supported by the switch-arm hinge and is rotative about its longitudinal axis and is cooperable with the said contact, a contact on the second insulated support and a projection on the switch-arm that is engageable by this contact, a rocker hinge pivot mounted on the second insulated support in spaced relation to the hinge pivot, a rocker movable about the rocker hinge pivot, a rocker swing pivot in the swing end of the rocker, a fourth pivot in the switch-arm hinge in spaced relation to the hinge pivot, a link in the form of a bellcrank pivoted on the fourth pivot and with one arm held by the rocker swing pivot and the other arm connected with the switch-arm, together with means to move the rocker and thereby to rotate the switch-arm and so change the pressures between the switch-arm and the contacts.

2. In an electric switch, a first insulated support and a jaw contact mounted thereon, a second insulated support and a hinge pivot mounted thereon, a switch-arm structure that comprises a switch-arm hinge movable about the hinge pivot and a switch-arm that is supported by the switch-arm hinge and is rotative about its own longitudinal axis and is cooperable with the jaw contact, a rocker hinge pivot mounted on the second insulated support in spaced relation to the hinge pivot, a rocker mounted on the rocker hinge pivot, a rocker swing pivot in the swing end of the rocker and movable only in a fixed arc about the said rocker hinge pivot, a fourth pivot supported by the switch-arm hinge in spaced relation to the hinge pivot, a link directly connecting the rocker swing pivot with the fourth pivot, the rocker swing pivot being movable with the rocker and the link through a certain part of their travel without causing change in the location of said fourth pivot, and members operable in response to motion of the link during the said certain part of its travel to cause rotation of said switch-arm about its longitudinal axis, together with mechanism to move the rocker and thereby to operate the switch.

3. In an electric switch, a first insulated support and a contact mounted thereon, a second insulated support and a hinge pivot mounted thereon, a switch-arm structure that is mounted on said hinge pivot and that includes a switch-arm hinge and a switch-arm that is rotatable about its own longitudinal axis and is cooperable with said contact, a rocker hinge pivot mounted on said second insulated support in spaced relation to the hinge pivot, a rocker mounted on said rocker hinge pivot, a rocker swing pivot in the swing end of the rocker and which is movable only in a fixed arc about the said rocker pivot, a fourth pivot in the switch-arm structure spaced away from the hinge pivot, a link connecting the rocker swing pivot with the said fourth pivot, and connecting means between the link and the rotatable switch-arm operable to rotate the switch-arm in response to motion of said link.

4. In an electric switch, a first insulated sup-

port and a jaw contact mounted thereon, a second insulated support and a hinge pivot mounted thereon, a switch-arm structure that is mounted on said hinge pivot and that includes a switch-arm that is rotatable about its own longitudinal axis and that is cooperable with said contact, a rocker hinge pivot mounted on said second insulated support in spaced relation to said hinge pivot, a rocker mounted on said rocker hinge pivot, a rocker swing pivot in the swing end of the rocker and which is movable only in an arc about the said rocker hinge pivot, a fourth pivot in the switch-arm structure spaced away from the hinge pivot, a link in the form of a bellcrank mounted on the fourth pivot and with one arm pivoted upon the rocker swing pivot and the other arm engageable with the switch-arm to rotate the switch-arm when in its closed position and thereby to vary the pressure between the switch-arm and the contact.

5. In an electric switch, a first insulated support and a contact mounted thereon, a second insulated support with a hinge pivot and also a contact mounted thereon, a switch-arm hinge mounted on the hinge pivot and supporting a switch-arm that is rotatable about its own longitudinal axis and that is cooperable with both of said contacts, a stationary rocker hinge pivot mounted on said second insulated support in spaced relation to said hinge pivot, a rocker mounted on said rocker hinge pivot, a rocker swing pivot in the swing end of the rocker, a fourth pivot mounted in the switch-arm hinge and spaced away from the hinge pivot, a link directly connecting the fourth pivot to the rocker swing pivot, connecting means between the link and the switch-arm, the rocker thereby being operable when the switch-arm is in fully closed position to rotate the switch-arm and thereby decrease the pressures between the switch-arm and both of said contacts.

6. In an electric switch, a first insulated support and a contact mounted thereon, a second insulated support and a hinge pivot mounted thereon, a switch-arm structure that comprises a switch-arm hinge movable about the hinge pivot and a switch-arm that is supported by the switch-arm hinge and is rotative about its longitudinal axis and is cooperable with the said contact, a contact on the second insulated support and a contact surface on the switch-arm that is engageable with this contact, a rocker hinge pivot mounted on the second insulated support in spaced relation to the hinge pivot; a rocker movable about the rocker hinge pivot, a rocker swing pivot in the swing end of the rocker, a fourth pivot in the switch-arm hinge in spaced relation to the hinge pivot, a link in the form of a bellcrank pivoted on the fourth pivot and with one arm held by the rocker swing pivot and the other arm connected with the switch-arm, together with means to move the rocker and thereby to rotate the switch-arm and so change the pressures between the switch-arm and the contacts.

7. In an electric switch, a first insulated support and a jaw contact mounted thereon, a second insulated support and a hinge pivot mounted thereon, a switch-arm structure that comprises a switch-arm hinge movable about the hinge pivot and a switch-arm that is supported by the switch-arm hinge and that is rotative about its longitudinal axis and is cooperable with the said contact, a second contact on the said second in-

sulated support and a projection on the rotative switch-arm that is engageable with the said second contact, a rocker hinge pivot mounted on the second insulated support in spaced relation to said hinge pivot, a rocker movably mounted upon the rocker hinge pivot, a rocker swing pivot in the swing end of the rocker and movable with the rocker only in a fixed arc about the said rocker hinge pivot, a link between the rocker swing pivot and the switch-arm structure with 10 a connection also to the rotative switch-arm, together with means to move the rocker and thereby to rotate the switch-arm and so change

the pressures between the switch-arm and the contacts.
